UNITED STATES PATENT OFFICE.

ERASTUS E. WINKLEY, OF LYNN, MASSACHUSETTS.

DETONATING MECHANISM.

Application filed May 6, 1918. Serial No. 232,991.

To all whom it may concern:

Be it known that I, ERASTUS E. WINKLEY, a citizen of the United States, residing at Lynn, in the county of Essex and State of Massachusetts, have invented certain new and useful Improvements in Detonating Mechanisms; and I do hereby declare the following to be a full, clear, and exact description of the invention, such as will enable others skilled in the art to which it appertains to make and use the same.

The present invention relates to an improvement in detonating mechanisms.

It has heretofore been proposed to provide a self-controlled vehicle carrying a charge of explosive mixture with a detonating mechanism which will act automatically to detonate the charge when the vehicle has reached a predetermined point. Certain types of these detonating mechanisms have been so constructed that their parts have not been operatively positioned to perform the detonating function until the vehicle provided with the detonating mechanism has been in travel for a predetermined length of time. This length of time is usually estimated to be sufficient for the vehicle to pass out from the friendly territory from which the vehicle is launched, and into the enemy territory toward which the vehicle is directed on its errand of destruction. These vehicles are subject to enemy fire, and consequently are liable to be disabled or destroyed before reaching their destination. So likewise, they may be disabled before the detonating mechanism, with which they are provided, is in condition to cause an explosion of the charge of explosive mixture they carry. In this case it is desirable that the charge of explosive mixture be detonated when the vehicle is disabled, on the chance that it is then in enemy territory.

Accordingly it is proposed by the present invention to provide a novel form of detonating mechanism of such construction and arrangement of parts that when a vehicle to which the detonating mechanism is applied is subjected to enemy fire, and a vital part of the vehicle is struck, for example, the rudder, propeller, or the engine, the det-

onating mechanism will be actuated to detonate the charge of explosive mixture carried by the vehicle. An essential part of this novel detonating mechanism is a covering member adapted to be applied in any convenient form to the exterior surface of the rudder, the propeller and the parts of the vehicle enclosing the engine, or such other vital mechanisms, so as to be interposed between the vital mechanism and the enemy gun fire. This covering member is so constructed that when a bullet, whether from an aerial gun, a rifle, or a machine gun penetrates it, or any other extraneous force disturbs or destroys its normal condition, the other parts of the detonating mechanism will be actuated to perform the detonating function. The improved detonating mechanism of the present invention is particularly pointed out in the appended claims, and a specific embodiment thereof is described in the following specification.

The several features of the present invention will be readily understood from the following description and accompanying drawings in which Fig. 1 is a side elevation of the rudder end of a rudder controlled vehicle having the improved detonating mechanism applied thereto, which mechanism is illustrated diagrammatically.

The improved detonating mechanism of the present invention is so constructed that in the event that the normal condition of the covering member is not destroyed or impaired, as by being penetrated by an enemy bullet, during the travel of the vehicle to its point of destination, the mechanism will continue in its normal or inactive condition and the other parts of the detonating mechanism will be ineffective upon the charge of explosive mixture. In addition to the detonating mechanism of the present invention, the vehicle will of course be provided with any usual or preferred form of detonating mechanism for the purpose of detonating the charge of explosive mixture when the vehicle reaches its point of destination, in case it does not encounter or is not struck by the enemy fire. The detonating mechanism of the present invention comprises a

hammer 5 and a trigger 6 for driving the hammer into the fuse of the charge of explosive mixture when the state or condition of the covering member is changed. The hammer 5 is mounted to slide vertically in a boss 7 carried by a casing 8 conveniently secured to the vehicle below the explosive mixture. The trigger 6 is mounted to slide vertically in a boss 9 formed in the bottom 10 of the casing 8 and is provided with a spring 10 interposed between the boss 9 and the head 11 of the trigger. In the drawing the hammer 5 and the trigger 6 are shown as constituting separate parts. This is simply for 15 the sake of convenience of construction, inasmuch as they may be made as a single member. So long as no part of the vehicle covered by the covering member of the improved detonating mechanism has been 20 struck by the enemy gun fire, the head 11 of the trigger 6 is held in such position as to keep the spring 10 compressed, that is to say, the trigger 6 is normally held cocked. The means for holding the spring 10 compressed depends upon the nature of the 25 covering material employed and the devices connected with it for releasing the trigger 6 to permit the spring 10 to actuate it to drive the hammer 5 into the fuse of the charge. In the illustrated embodiment of 30 the invention the trigger 6 is shown as constituting the armature 15 of a solenoid, generally indicated at 16. The solenoid 16 is energized by a battery 17 placed in a circuit 18 formed by a continuous electric wire 20 attached to a fabric or some other pliable sheet material 21 in such manner that both the sheet material 21 and the wire 20 constitute the covering member. The electric wire 35 40 45 50 55 60 65 70 75 80 85 90 95 100 105 110 115 120 125 130 20 is folded upon itself in such manner that the folds thereof are less than the thickness of a rifle or machine gun bullet apart. The wire 20 is shown as plaited, as it would be if it were woven into the fabric or sheet material as a weft thread, but it may, of course, be folded upon itself in any other convenient manner, as in convolutions or involutions. The covering member is shown as extending partly onto the rear end of the vehicle 22 and partly onto the rudder 24, thereby covering over the hinge connections 25 and their adjacent parts and thus being interposed between these parts, which are vital to the progress of the vehicle, and the enemy gun fire. The rear end of the rudder will not be covered, because it is obvious that it may be perforated without seriously impairing the operativeness of the rudder. It will be apparent that the covering member may be as readily applied to other portions of the vehicle, so as to be interposed between the vital parts of the vehicle and the enemy fire.

The circuit 18 formed by the electric wire 20 will normally be closed, so that the sole-

noid 16 will be energized by the battery 17 to hold the armature 15 in such position as to normally keep the spring 10 under compression. If now one of the folds of the electric wire 20 is severed by a bullet, the circuit will be broken so that the battery 17 will no longer energize the solenoid 16. Thereupon, the armature 15 being free to move, the spring 10 will act to drive the hammer 5 upwardly into the fuse of the charge, thereby detonating the explosive mixture.

The covering member of the present detonating mechanism has been shown and described as a sheet material having attached thereto a wire forming a normally closed electric circuit, upon the breaking of which the other parts of the detonating mechanism are actuated to perform the detonating function. It will be understood that this feature of the invention is not limited to the specific covering member shown and described, and the devices directly connected with it, inasmuch as the covering member and the devices controlled by it to actuate the hammer may be any one of many equivalent structures which will operate, upon a disturbance of their normal condition by an extraneous force, to actuate the hammer or other device used to ignite the fuse of the charge of explosive mixture.

Having thus described the invention, what is claimed as new, is:—

1. A detonating mechanism for vehicles comprising a hammer, means normally held in condition to actuate the hammer, and a covering member adapted for application to surfaces of the vehicle subject to the action of extraneous force, said covering member being connected with the hammer actuating means in such manner that when a normal condition of a component part of the covering member is destroyed by the action of extraneous force, the hammer actuating means is permitted to perform its hammer actuating function.

2. A detonating mechanism for vehicles comprising a covering member consisting of a sheet of pliable material adapted to be applied to the vehicle and having attached thereto an electric wire constituting a normally closed circuit, said wire being folded upon itself in such manner that the folds thereof are less than a bullet thickness apart, a solenoid in the circuit, and a hammer arranged to be actuated by the armature of the solenoid when the circuit is broken.

3. A detonating mechanism for vehicles comprising a covering member adapted to be applied to the vehicle so as to receive the effect of gun fire directed at the vehicle, a hammer, and means connected with the covering member and operative to actuate the hammer when the covering member is penetrated.

4. A detonating mechanism for vehicles comprising means for detonating an explosive mixture; means for actuating the detonating means; and a covering member connected with the actuating means and adapted for application to surfaces of the vehicle subject to the action of extraneous force,

said covering member acting to permit the actuating means to actuate the detonating means when the covering member has been 10 penetrated by an object making a hole therein as large as a bullet hole.

ERASTUS E. WINKLEY.
